UNITED STATES PATENT OFFICE.

WILLIAM H. WOOD, OF SOUTH EUCLID, OHIO

STORAGE BATTERY.

No Drawing.

Application filed November 22, 1920. Serial No. 425,828.

To all whom it may concern:

Be it known that I, WILLIAM H. Wood, a citizen of the United States, residing at South Euclid, in the county of Cuyahoga and State of Ohio, have invented a certain new and useful Improvement in Storage Batteries, of which the following is a full, clear, and exact description.

This invention relates to storage batteries and has for its object the provision of an electrical accumulator of the lead type in which the chemical and electrical action can be carried further into the body of the plate than in the usual type of construction, thus enabling the use of thicker plates; and wherein the breaking out and disintegration of the paste may be largely or entirely avoided, and wherein the production of a hard, impenetrable film of sulphate shall be rendered impossible. A further object of the invention, which is substantially the corollary of the foregoing, is the provision of a storage battery having a very great capacity per unit of weight coupled with an extremely high discharge rate with a minimum of injury to the elements, whereby such uses as the cranking of automobile engines can be served with batteries of reduced weight, size, and expense; and additional objects and advantages of the invention will become apparent as the description proceeds.

In my application filed March 31, 1920, Serial No. 370,319, I described a storage battery of the lead type wherein the lead oxide was mixed with short fibers of "pulled wool," this being a generic term for wool which has been loosened from the pelt by means of chemicals and thus removed by pulling, instead of by shearing as in the usual manner; and when the chemical used is of an alkaline nature, such as caustic soda or sodium sulphite, a secondary result of the chemical action is the solution and removal of many of the exterior scales with which each strand is covered. Wool or other mammalian hair having these scales thereon in their original closely adherent position is entirely useless for this purpose from the fact that such scales are impenetrable and do not permit any access of the electrolyte to the surrounding parts; but upon the removal or loosening of such scales, the desired action can take place, each strand serving as a little wick to place the interior portions of the plate in communication with the exterior liquid.

In my former application I particularly suggested the use of wool which had been pulled by the use of the alkaline substances above mentioned, or other mammalian hair which was treated in a like manner for the removal or thorough loosening of the scales, although I did not restrict myself to such chemicals and also recommended the use of other wool materials, such as felters' waste, and pointed out that it was not necessary to remove all the scales, and that old and frequently used wool wherein the scales had been largely broken away by mechanical abrasion required little or no chemical treatment before use.

I have discovered that felters' waste or felters' wool, if properly prepared, or other mammalian hair prepared in a similar manner, is even better from some points of view for use in battery plates than wool whose scales have been loosened by such a reagent as sodium sulphite. In the production of felt the wool or hair is first "carroted," that is, treated for a time with an astringent substance which shrivels the scales and causes them to become curled away from the core of the strand but without becoming wholly removed or even seriously loosened. The chemical is then removed by washing, leaving each strand studded with these little sharp prongs which become interlocked so tightly together when the product is matted and compressed into sheets as to be practically untearable. In the best felts this "carrotting" is effected by the use of mercuric nitrate, and the most fastidious manufacturers secure their raw material in pelt form and submit the entire pelt to the action of the mercuric salt which soon loosens the hair so that it is removed by pulling and is therefore entitled to be called "pulled wool." Others secure their raw product in sheared form and treat it subsequently to its removal from the pelt, and use other chemicals for upcurling the scales to avoid the expensive and poisonous mercury salt. By whatever process it be prepared, the shriveling and curling of the scales enables the necessary contact between the active material and the pervious core of the hair, while the interlocking of the scales with such active material binds the same together more tightly than is possible in the absence of those scales. The core of such hair is highly elastic and yields without breaking to the expansion and contraction of the active ma-

terial, while, being insoluble in sulphuric acid of any strength which is used in batteries, it produces porosity without possibility of deterioration.

6 I do not restrict myself to the use of wool from the sheep or goat, or any other hair customarily used in the arts such as that of the camel, llama, beaver, mink, muskrat, coney, or coypu, but may equally employ the hair of the horse, ox, dog, or man, all of which are composed of the same essential substances arranged in the same manner and are intended to be covered hereby.

10 However, I do not advocate the use of excessively fine hairs, partly for the reason that their smallness interferes with their wick-action, and partly for the reason that the closeness with which their scales are set renders it difficult to secure close contact between the paste and core. I prefer the moderately coarse hair of the equine, bovine, canine or human species, but do not restrict myself thereto since common sheep's wool when properly treated serves excellently, 15 and I define the word "hair" in my claims as including the epidermoid outgrowths of vertebrate terrestrial mammals.

20 Also it is not important to my invention who it is that originally treats the wool or hair or for what uses it may have been designed or employed before being made into battery plates. It is the same thing so far as my invention is concerned whether fresh and unworked worsted is treated in this way 25 for this primary purpose or whether material is employed which was primarily designed for felting or even made into felt and afterward disintegrated. As an example of my invention I take wool or nutria which 30 has been carotted in any customary manner

for felters' use, chop it to a fiber length of one-eighth inch (more or less) and mix the same in proper proportion with the lead compound (for example $\frac{1}{5}$ th of one per cent, more or less by weight). The plates 45 are then pasted, set, assembled, formed, and charged in the usual manner. The plates can be made thicker than usual, will show a very great capacity, high rate of charge and discharge, great overcharge capacity, freedom from sulphating, great permanence of 50 form, and no tendency to scale or disintegrate, while the proportion of active material to grid can be much increased.

It will be understood that I do not limit myself to the use of any one chemical or process in the treatment or "carrotting" of the hair, wool, or other raw material, and generally that I ascribe to my claims the broadest meaning that their terms will bear, 55 reference being had to the definitions hereinbefore contained.

Having thus described my invention, what I claim is:

1. A composition of matter for the plates 65 of storage batteries consisting essentially of oxide of lead mixed with carotted hair.
2. A composition of matter for the plates of storage batteries consisting essentially of oxide of lead mixed with animal hair whose 70 external scales have been opened outwardly but without complete removal.
3. A plate for a storage battery consisting essentially of a lead compound impregnated with comminuted animal hair studded with 75 outwardly projecting shriveled scales.

In testimony whereof, I hereunto affix my signature.

WILLIAM H. WOOD.
